LOUIS F. KATONA, OF LOS ANGELES, CALIFORNIA.

SEWER-FLUSHING DEVICE.

Application filed November 5, 1927. Serial No. 231,360.

This invention relates to an improved type of sewer flushing device and is particularly directed to that general class of device which automatically functions to periodically effect 5 a flushing of the sewer.

A device of this general character comprises a flushing well having a valved outlet communicating with the sewer conduit to be flushed, said valve being arranged to 10 be automatically opened by a tripping mechanism controlled by a predetermined head of water which is permitted to flow into the well at a predetermined rate. The water in the well, when it reaches a predetermined 15 level flows into a tripping pan or bucket, which when it receives a sufficient quantity of water to overbalance the weight of the valve, serves to open said valve to allow the main body of water to flow into the 20 sewer conduit, thereby flushing the sewer.

In one type of device heretofore employed for this purpose, the valve is entirely submerged in the body of fluid in the well and consequently is forcefully held closed by the 25 weight of the fluid above the valve, and for this reason the tripping pan or bucket must be of considerable size in order to hold a volume of fluid sufficient to overcome the pressure of the fluid head upon the valve as 30 well as the weight of the valve itself. As soon as an overbalance is effected the valve opens and it would be supposed that with the opening of the valve the pressure of the fluid head upon the valve would be counter- 35 balanced by a like pressure below the valve and the mechanism would be easily retained in open position by the bucket, but, the action of the large volume of fluid rushing through the valve opening will produce a 40 suction tending to draw the valve member down upon its seat, provisions must be made to counteract such suction influences. In some instances this is in a measure ac- 45 complished by arranging the bucket so that the fluid discharged from the well strikes the top cover plate of the bucket so as to hold the valve open until the main body of water is discharged. By this construction it is obvious that it is not only necessary to 50 have a bucket which will hold enough fluid to overbalance the weight of the heavy valve, but said bucket must also be of sufficient capacity to overcome the weight of the head of fluid above said valve. This has been 55 found disadvantageous inasmuch as the space in the well is limited, and the cost of a large

bucket, which necessarily must be made of relatively expensive non-corrosive material, is prohibitive.

In other types of devices it has been proposed to overcome these disadvantages by providing the valve with a hollow sleeve which is closed at its lower end and which extends upwardly to a point above the maximum level of the fluid in the well so as to 60 relieve the valve of the fluid head pressure and thus enable the use of a smaller bucket. However, while this expedient does relieve the valve of the fluid head pressure, it presents another very serious difficulty in that 65 it provides a valve of constant weight, that is, as the fluid head pressure is at no time exerted upon the valve, said valve is only held closed by its own weight, which is constant. With such an arrangement the mechanism is very delicately balanced and the suction action of the released fluid will close 70 the valve before the well is discharged. This is due to the fact that the valve, which in this instance closes the lower end of the 75 hollow sleeve, is subject to the full suction action of the outrushing fluid.

It is therefore an object of the present invention to provide a flushing device of the general character above described, in which 80 the fluid head pressure is not exerted to hold the valve on its seat and at the same time to provide a tubular valve providing a constant communication between the sewer conduit and the space in the well above the maximum fluid level so as to minimize the suction action of the outrushing fluid, upon the valve, thus producing a device which 85 will be positive in its operation.

Another object is to provide a flushing 90 device in which the mechanism is arranged to provide an unobstructed outlet for the flushing fluid when released by the opening of the valve.

Various other objects and advantages will 95 be more fully apparent from the following description of the accompanying drawing which forms a part of this disclosure and which illustrates a preferred form of embodiment of the invention.

Of the drawing:

Fig. 1 is a vertical section disclosing the flushing device as mounted for operation within the well of a sewerage system.

Fig. 2 is an enlarged detail section taken 110 on the line 2-2 of Fig. 1.

In the drawing, 10 designates a well of

any particular desired design, communicating with a pit 11 located at the head of a sewer conduit 12 and having an inclined bottom wall in order to insure a perfect 5 drainage to said sewer conduit. The top of the well has a man-hole ring 13 closed by an inner man-hole cover 14 and an outer man-hole cover 15 preferably located approximately level with the street.

10 Leading into the well 10 near its top, is a water pipe 16 provided with a valve 17 which may be conveniently reached from the man-hole and be regulated to permit water to flow into said well at any desired 15 rate.

15 Mounted between the well 10 and the pit 11, is a false bottom plate 18, preferably formed of wood which has been treated with asphalt or other suitable material to render 20 it water tight, said bottom plate being preferably calked in a metal frame 19 which is securely anchored in the masonry of the well. This bottom plate 18 forms a support for the entire mechanism of the device 25 and has an opening 20 therein constituting a discharge port establishing direct communication between the well and the sewer conduit. An annular tapered valve seat 21 is secured in said opening 20 by screws 22 and 30 cooperating with said seat is a tubular valve 23 having a tapered valve ring 24 preferably formed of rubber and adapted to engage said seat when the valve is closed. The upper sleeve portion 25 of the valve, which 35 extends to a point above the maximum water level, is of a uniform diameter throughout its length and is of substantially the same diameter as the valve ring 24 so that the fluid head will not exert a downward pressure thereon such as would tend to 40 forcefully hold the valve closed.

45 The top end of the valve sleeve is connected to one end of a walking beam 26 by a link 27 which at its upper end is pivoted to said walking beam at 28 and at its lower end is pivoted on a pivot rod 29 diametrically disposed in opposite bosses 30 formed on opposite sides of the upper end of the valve sleeve wall. Said link is maintained 50 centrally disposed on said pivot rod 29 by spacing sleeves 31 and the pivot rod is maintained against displacement by plugs 32 screwed into the outer ends of the bores of said bosses after the rod is in place.

55 The walking beam 26 is pivotally supported between its ends on a pivot pin 33 carried by an arm 34 of a tubular standard 35, said standard being hollow throughout its length and provided near its lower end 60 with an annular flange 36 by which it is secured to the upper surface of the bottom plate 18, by suitable bolts 37. This standard has a depending skirt 38 which extends through a hole in said bottom plate so as 65 to establish communication between the in-

terior of the hollow standard and the pit 11 below said plate, and near its upper end is provided with an overflow port 50, the location of which determines the maximum fluid level in the well.

70 A downwardly extending bracket 39 is secured to the under surface of the false bottom plate 18 by suitable bolts 40 and an actuating pan or bucket 41 is provided with hinge lugs 42 engaging a pivot rod 43 carried by said bracket, so that said bucket is pivotally supported within the pit 11 below the tubular standard 35. Extending upwardly from the horizontal portion of the floor of the bucket 41 is a bail 44 which is 75 engaged by a hooked lower end of a rod 45. This rod 45 extends upwardly through the tubular standard 35 and is connected to an opposite end of the walking beam 26 by a universal connection, to be later described. 80

85 The floor of the bucket 41, from the location of the bail 44 outwardly, tapers upwardly to a point close to the upper edges of the side walls of the bucket and a cover plate 46 is secured to said side walls and 90 extends across from one side wall to the other and rearwardly substantially one-half the length of the bucket. This cover plate, together with the side walls and the floor plate of the bucket, defines a drain opening 47, the purpose of said cover plate being to prevent an emptying of the bucket as soon as it is tripped and to permit the fluid in the bucket to drain therefrom after completion of the flushing operation, so the 95 bucket may be then returned to normal position by the weight of the valve. 100

105 A bracket 48 is secured to the standard 35 and surrounds the valve sleeve 25 so as to guide the valve in its movements from and towards the valve seat.

110 The universal connection between the rod 45 and the walking beam 26 comprises a trunnion member 51 having opposed trunnions 52. The end of the walking beam 115 is bifurcated to provide opposed limbs 53 and these are provided with notches 54 in which rest the respective trunnions 52 of said trunnion member 51. An extension member 55 is tightly screwed upon the upper end of the rod 45 and has a screw-threaded shank which extends through an enlarged vertical bore in the trunnion member 51 and is screw-threaded into a short cylindrical member 56 seated in a concentric concave seat 57 (see Fig. 2.) in the upper surface of the trunnion member. 120

125 This construction provides a universal connection and a means by which the effective length of the rod 45 may be varied, such variation being accomplished by screwing the short cylindrical member 56 downwardly or upwardly upon the screw-threaded shank of the extension member 55.

130 In operation, the well is filled with water

from the supply pipe 16. As the valve 23 is seated upon the valve seat 21, the level of the water will gradually rise until it has reached the overflow opening 50 in the 5 tubular standard 35. When the water has reached this point, it will overflow into and down through the standard into the bucket 41. This bucket will gradually fill and when the weight of water therein is 10 sufficient to overcome the weight of the valve and its connections, the bucket will be lowered and the valve will be raised to release the water in the well, whereupon said water will rush through the valve opening into 15 the pit 11 and into the sewer conduit to effect a flushing of the sewer.

As the valve opening is relatively large, this outrush of the water will be quite rapid and would tend to create a severe suction 20 upon the valve if said valve were of such construction as to entirely close the lower end of the valve sleeve 25, but with the present tubular valve construction, which is open throughout its length, such suction influence is minimized by reason of the fact 25 that the interior of the valve is open to the atmosphere in the well above the body of water therein.

It will be evident that as soon as the valve 30 is opened, the water will enter the bore of the valve and seek to attain a level therein coincident with the level of the main body of water in the well, but in actual practice, certain conditions affect the operation to produce an action which is dependent directly 35 upon the particular form of tubular valve employed.

It has been found that when the valve of the device herein disclosed, is first opened, a 40 high back-pressure is created and that such back-pressure exerts its energy to project the discharged water backwardly and upwardly through the tubular valve and the tubular standard until the energy of said back-pressure 45 is spent. Thereafter the water discharges into the sewer until the well is empty.

This back-pressure may of course be due to an obstruction in the sewer, which obstruction would prevent an escape of the air in the pit and the sewer, ahead of the flushing water, in which event this trapped air would be very suddenly compressed to build up a high-back pressure, unless the obstruction yield promptly to the force of the water. However, it has been found that a high 55 back-pressure is developed even in instances in which the sewer is not obstructed, and this condition is believed to be due to the normal circulation of air in the sewer system. It is well known that the air in a sewer system flows towards the highest points therein, that is, towards the man-hole wells included in the system, with considerable 60 velocity, in fact the circulation of air

in ordinary sewer systems is so pronounced that a constant roaring sound is produced therein. This being so, it will be evident that in the operation of the herein disclosed device, when the valve is opened the out-rushing water must first reverse the direction of flow of the air. In actual practice it has been found that this meeting of the out-rushing water with the incoming air causes a sudden building up of a high back-pressure 70 which will exert its energy in the same manner as above explained. After the energy of such back-pressure is spent, the main body of water in the well will discharge into the sewer. During the discharge a very pronounced suction is created at the valve opening 75 20 and the valve closing influence of such suction is minimized by reason of the fact that the upper end of the valve is open to the atmosphere. 80

With a valve entirely closed at its lower end, the full force of this suction would be exerted directly upon the valve itself and the valve would be prematurely closed. With the tubular valve employed in the present 90 invention, the suction acts mainly upon the body of water within the valve bore and with the upper end of said bore open to the atmosphere, the result is merely a lowering of the level of the water in said valve bore 95 instead of a pronounced downward pull on the valve itself. Under these conditions, the level of the water in said bore will ordinarily be considerably below that of the main body of water in the well. 100

From the above it should be evident that the employment of a tubular valve in a sewer flushing device of this character constitutes a radical departure from and a marked improvement over the constructions 105 heretofore employed in devices of this general character and that the construction herein disclosed provides a device which is vastly more positive in its operation than those of the type disclosed in the prior art patents 110 above referred to.

To further guard against a premature closing of the valve, the bucket 41 is positioned with its cover plate 46 directly below the valve opening 20 so that the weight of the out-rushing water will strike upon said cover plate and assist in holding the bucket depressed until the well is emptied. After 115 the well is emptied, the water in the bucket will drain through the drain opening 47, whereupon the parts will return to their 120 normal positions.

While the form of mechanism herein illustrated and described is fully capable of fulfilling the objects primarily stated, it is to be understood that I do not wish to limit the invention in this regard, for it is susceptible of embodiment in various other forms all coming within the scope of the claims, 125 which follow. 130

I claim as my invention:

1. In a sewer flushing device, the combination of: a well adapted to contain a body of flushing fluid and having an outlet communicating with a sewer; a tubular valve closing said outlet; and means for opening said valve to permit a discharge of said fluid into said sewer, said valve being extended upwardly above the maximum level of said body of flushing fluid and having its bore open at both ends, whereby said bore is in constant communication with said sewer and with the atmosphere above said body of fluid, and said upward extension of said valve having an external diameter approximately equal to the maximum diameter of the valve so that the fluid in the well will not exert on said valve an appreciable downward pressure tending to hold it closed.
  2. In a sewer flushing device, the combination of: a well adapted to contain a body of flushing fluid and having an outlet communicating with a sewer; an overflow for said well; a tubular valve closing said outlet; and automatic means for opening said valve to permit a discharge of said fluid into said sewer, said means being operated by the overflow fluid when the weight thereof becomes sufficient to overbalance the weight of the valve, and said valve being extended upwardly above the maximum level of said body of flushing fluid and having its bore open at both ends, whereby said bore is in constant communication with said sewer and with the atmosphere above said body of fluid, and said upward extension of said valve having an external diameter approximately equal to the maximum diameter of the valve so that the fluid in the well will not exert on said valve an appreciable downward pressure tending to hold it closed.
  3. In a sewer flushing device, the combination of: a well adapted to contain a body of flushing fluid and having an outlet communicating with a sewer; an overflow for said well; a tubular valve closing said outlet; and an actuating bucket positioned to receive the overflow fluid and operatively connected with said valve so as to automatically open said valve when the weight of the overflow fluid in said bucket is sufficient to overbalance the weight of the valve, said valve being extended upwardly above the maximum level of said body of flushing fluid and having its bore open at both ends, whereby said bore is in constant communication with said sewer and with the atmosphere above said body of fluid, and said upward extension of said valve having an external diameter approximately equal to the maximum diameter of the valve so that the fluid in the well will not exert on said valve an appreciable downward pressure tending to hold it closed.
- external diameter approximately equal to 60 the maximum diameter of the valve so that the fluid in the well will not exert on said valve an appreciable downward pressure tending to hold it closed.
4. In a sewer flushing device, the combination of: a well adapted to contain a body of flushing fluid and having a pit communicating with a sewer; a false bottom plate positioned between said well and said pit and provided with a valve opening establishing communication between said well and said pit; a tubular valve closing said opening and extended upwardly to a point above the maximum level of said body of flushing fluid; a tubular standard positioned in said well and secured to said bottom plate, the bore of said standard communicating with said pit and the upper wall thereof having an overflow port for determining the maximum level of said body of flushing fluid; a hingedly supported bucket positioned in said pit in position to receive the overflow fluid from said standard; a rod connected with said bucket and extending upwardly through said tubular standard; a walking beam pivoted on said standard and pivotally connected at its respective opposite ends to said rod and to said tubular valve, the bore of said tubular valve being open at both ends, whereby said bore is in constant communication with said sewer and with the atmosphere above said body of fluid, and said upward extension of said valve having an external diameter approximately equal to the maximum diameter of the valve 90 so that the fluid in the well will not exert on said valve an appreciable downward pressure tending to hold it closed.
  5. A tubular valve member adapted to be positioned in a body of flushing fluid in a well of a sewer system and to close a discharge opening leading to the sewer, said valve being of sufficient height to extend above the maximum level of said body of fluid and the bore of said valve being open 100 at both ends, whereby said bore will be in constant communication with said sewer and with the atmosphere above said body of fluid, and said upward extension of said valve having an external diameter approximately 105 equal to the maximum diameter of the valve so that the fluid in the well will not exert on said valve an appreciable downward pressure tending to hold it closed.

In testimony whereof, I have hereunto set my hand at Glendale, California, this 27th day of October, 1927.

LOUIS F. KATONA.
